UNITED STATES PATENT OFFICE.

FREDRICK WILLIAM EISENBERG, OF ANN ARBOR, MICHIGAN.

TAILOR'S CHARCOAL-IRON.

SPECIFICATION forming part of Letters Patent No. 378,297, dated February 21, 1888.

Application filed May 12, 1887. Serial No. 237,960. (No model.)

To all whom it may concern:

Be it known that I, FREDRICK WILLIAM EISENBERG, of Ann Arbor, in the county of Washtenaw and State of Michigan, have invented new and useful Improvements in Tailors' Charcoal-Irons; and I do hereby declare that the following is a full, clear, and exact description thereof, reference being had to the accompanying drawings, which form a part of this specification.

This invention relates to certain new and useful improvements in tailors' charcoal-irons.

The invention consists in the peculiar construction, arrangement, and combination of the various parts, all as more fully hereinafter set forth.

Figure 1 is a side elevation. Fig. 2 is a vertical section on the line *x x* of Fig. 4. Fig. 3 is a cross-section on the line *y y* of Fig. 1. Fig. 4 is a rear end elevation. Fig. 5 is a horizontal section on the line *z z* of Fig. 2.

In the accompanying drawings, which form a part of this specification, A represents the body of the iron or "goose," which is provided 25 at its toe with a rigid top plate, B, carrying the neck C.

D is the adjustable cover, which consists of the main plate *a*, from which rise the handle-standards E, and in which is secured the handle F.

b is the supplemental plate of the cover D, which is rigidly secured upon the plate *a*, and between the two plates is placed a filling, *c*, of asbestos or other suitable non-conducting material that will prevent heat radiating from the goose from overheating the handle. This cover is hinged to the rear wall of the body of the iron, and is provided with a slide, G, beneath the handle, such slide being arranged to 35 engage with a proper opening in the foot of the neck C. (Shown in Fig. 2.)

H is a slatted grate, the front end of which is supported by the inwardly-projecting lugs *d*,

while its rear end is provided with a deflecting-plate, I, the upper flanged edge, *e*, of which 45 rests upon the supports *f* in the corners of the heel of the iron at each side of the draft-opening, which latter is closed or unclosed by the draft-doors J.

K is the bottom of the iron, which at the 50 heel is properly hinged or pivotally secured to the rear wall of the body A, and is provided at its front end or toe with an upwardly-projecting lug, L, which enters a correspondingly-shaped recess in the toe of the iron. This 55 bottom plate is provided with a beveled flange, *h*, which fits over, when closed, the beveled lower edge of the body of the iron, as shown in Fig. 3. This makes a tight joint when the parts are closed together, and prevents ashes 60 from falling out of the iron upon the fabric being operated upon.

M is a securing-pin which passes down through the toe of the iron, the lower end of such pin being threaded to engage with a threaded 65 hole in the upper end of the lug L, by means of which the bottom is secured in place.

In this construction the operator can by releasing the retaining-pin M drop the bottom and allow the ashes that may have accumulated thereon to fall out without disturbing 70 the grate or the fire thereon.

What I claim as my invention is—

In a tailor's iron, the combination of the body A, rigid top plate, B, neck C, cover D, 75 handle F, locking-slide G, slatted grate H, deflecting-plate I, draft-doors J, hinged bottom K, formed at one end with upwardly-projecting lug L, and threaded locking-pin M, the parts being constructed, arranged, and operating substantially in the manner and for the purposes set forth.

FREDRICK WILLIAM EISENBERG.
